ATTY

UNITED STATES PATENT OFFICE.

JAMES ANDREW TAYLOR, OF GALT, ONTARIO, CANADA.

LADDER.

Application filed December 17, 1921. Serial No. 523,187.

To all whom it may concern:

Be it known that I, JAMES A. TAYLOR, a resident of the city of Galt, in the county of Waterloo, in the Province of Ontario, Canada, a subject of the King of Great Britain, have invented certain new and useful Improvements in Ladders, of which the following is a specification.

This invention relates to ladders made up 10 of a number of similar units, and which are hung from a roof, window or other elevated position, and my object is to devise an improved construction which will be simple to construct, and which will have the requisite 15 stiffness to enable the ladder to be placed in position from the ground.

I attain my object by means of the constructions hereinafter described and illustrated in the accompanying drawings in 20 which—

Fig. 1 is a front elevation of my improved ladder;

Fig. 2 a side elevation of the same;

Fig. 3 a side elevation showing a modified 25 construction;

Fig. 4 a side elevation of part of a ladder showing the preferred form of stiffening bar secured thereto;

Fig. 5 a front view of the same;

Fig. 6 a detail side elevation of another 30 form of stiffening bar and its connection;

Fig. 7 a detail side elevation showing the use of a wooden stiffening bar; and

Fig. 8 a detail of a modified form of the 35 construction shown in Fig. 1.

In the drawing like numerals of reference indicate corresponding parts in the different figures.

The ladder will comprise a number of 40 similar sections, the number and size of the sections depending entirely on the position in which the ladder is used and the use to which it is put.

Each section is formed of an integral piece 45 of wire comprising the rung 1 and the upwardly extending sides 2. In the upper section of the ladder the sides 2 will terminate in hooks 3 adapted to catch on a roof, window ledge, or other suitable object.

It should be noted, however, that at the 50 point of connection between the rung and sides a small loop 4 is formed.

The upper end of each side 2 is bent behind the rung 1 and in front of the side 2 of 55 the adjacent section and thence rearwardly,

then upwardly and then forwardly to form a large loop 5, the object of which loop is to hold the ladder spaced from the wall to which it is applied. The end of the side may then be twisted around the side of the 60 adjacent section as shown in Figs. 1 and 2 or it may be clamped to the side by means of clamps 6 as shown in Fig. 3. Where the ladder is likely to be often taken apart, the construction shown in Fig. 3 is the preferable 65 one.

In Fig. 1, it will be noted that the sides of each section gradually taper towards one another towards their upper ends. If it is desired that the sides be parallel, an inwardly directed loop 7 is formed, as shown in Fig. 8, just below the spacing loop 5 in which the rung of the adjacent section engages.

While for short ladders the construction 75 shown possesses sufficient stiffness to enable it to be placed in position from below, for longer ladders it is preferable to provide additional stiffening means, which might be of various forms. The preferred form is 80 shown in Figs. 4 and 5 in which a channel shaped stiffening bar 8 is shown, the ends of the spacing loops 5 being received in the channel, and the sides of the channel being bent inwardly between the sides of the loops 85 as at 9 to prevent the withdrawal of the loop.

In Fig. 6 the stiffening rod is simply a wire or slight bar, which is secured to the ends of the loops by clamping members 90 similar to the clamps 6.

In Fig. 7 I show the use of a wooden bar 10 as the stiffening member, which is secured to the spacing loop 5 by a hook or staple 11.

The stiffening members may be the whole 95 length of the ladder, or may be long enough to connect any number of sections as may be desired.

From the foregoing description and drawings, it will be noted that the spacing loops 100 5 are used to provide stiffness in the ladder, that the various sections of the ladder are so connected that there is no danger of them pulling apart; that there is no strain on the spacing loops; and that when the stiffening bars are employed a very stiff ladder is secured which may easily be placed in position 105 from below.

As the lower end of the ladder will usually 110 be a short distance above the ground, I pro-

vide at each side of the lowermost section a member 11' to which another short ladder may be secured. Each member 11' will also be formed with a spacing loop 5.

5. What I claim as my invention is:—

10. 1. A ladder comprising a plurality of sections of similar construction, each section being formed of an integral piece of metal comprising a rung and two sides, the free end of each side passing behind the rung and in front of the side of the adjacent section adjacent the rung and then bent rearwardly to form a spacing loop, the free end of the loop being secured to the side of the adjacent section a distance from the rung.

15. 2. A ladder comprising a plurality of sections of similar construction, each section being formed of an integral piece of metal comprising a rung and two sides, a loop being formed at the junction of each side with the rung, the free end of each side passing behind the rung and in front of the side of the adjacent section adjacent the rung and

secured to the side of the adjacent section a distance from the rung.

3. A ladder comprising a plurality of sections of similar construction, each section being formed of an integral piece of metal comprising a rung and two sides, the free end of each side passing behind the rung and in front of the side of the adjacent section adjacent the rung and then bent rearwardly to form a spacing loop, the free end of the loop being secured to the side of the adjacent section a distance from the rung; 30 and a stiffening member of channel-shape in cross section secured to a plurality of said spacing loops, the legs of the channel being inwardly bent to engage the spacing loops. 35

Signed at Galt, Ontario, this 7th day of 40 December, 1921.

JAMES ANDREW TAYLOR.
